UNITED STATES PATENT OFFICE.

GEORGE CHAPMAN, OF ARLINGTON, NEW JERSEY.

COIN LOCK.

Application filed June 11, 1921. Serial No. 476,711.

This invention relates to coin locks such as are commonly employed for unlocking a door when a coin is inserted therein.

The object of the invention is to provide a coin lock of extreme simplicity of construction but highly efficient for the purpose for which it is designed, and wherein economy of space and cost of manufacture is obtained.

10 A further object of the invention is to provide a lock of the character set forth wherein few parts are employed and the control of the lock is effected through the coin itself.

15 A further object of the invention is to provide a lock of the above character which will respond to coins and other tokens of a given size, but which will reject coins of other sizes.

20 Further objects of the invention will appear more fully hereinafter, as set forth in the accompanying drawings, and pointed out in the appended claim.

Referring to the drawings:

25 Figure 1 is a view of a coin lock embodying my invention, partially broken away, looking from the exterior.

Fig. 2 is a sectional view of the same.

Fig. 3 is a view in elevation of the interior 30 of the front portion of the lock.

Fig. 4 is a similar view of the rear portion of the lock.

Fig. 5 is a sectional view taken on the line 5—5 of Fig. 4 and looking in the direction of the arrows.

Fig. 6 is an enlarged view with the bolt structure shown in Fig. 4.

The same part is designated by the same reference character wherever it occurs 40 throughout the several views.

It is among the special purposes of my present invention to provide a lock which will permit the actuation thereof at all times from the interior of the door, or the like, 45 which is to be locked, but which will permit the actuation of the lock from the exterior only when a coin of a predetermined size is inserted therein. As generically indicated hereinbefore, I form the lock of my invention in two parts; namely, a rear plate 1 which is adapted to be screwed or otherwise suitably secured to the door through holes 50

55 2. Formed on the face of the rear plate 1 are lugs 3 beveled interiorly to form a dove-tail guideway for the bolt 4 which is provided with the usual beveled head 5. A

handle 6 is secured to a shaft 7 which extends through the door to which the plate is fastened, and the shaft has has mounted on the interior thereof a collar 8 which has secured thereto or formed integrally therewith a bell crank lever one end of which is provided with a pin 9 extending parallel to the axis of the shaft 7 and positioned therebelow means for attachment, for example, 60 an orifice 10, to one end of a tension spring 11, the opposite end of which is secured in any suitable manner, for example, by means of a screw 12 to a boss 13 formed integrally with or otherwise secured to the plate 1 and 65 extending at right angles relative thereto. The other end 14 of the bell crank lever extends through slot 15 cut through the lower lug 3 and is rounded, as shown, to form a socket connection with the bolt 4 through 70 the medium of a rounded depression 16 cut in the lower edge thereof.

From the foregoing it will readily be apparent that when the handle 6; that is, the handle of the interior of the door, is rocked, 80 say clockwise, the shaft 7 is rocked coincidently therewith, and, consequently, the bell crank is rocked, the leg 14 thereof moving clockwise and drawing the bolt 4, and, consequently, its head 5, toward the right to 85 unlock the door. A coin guide bell crank 17 is pivotally secured to the rear plate 1, as at 18, with one leg 19 thereof extending over the face of the bolt 4 and adapted to be moved towards the right when the bolt is 90 drawn to the right. The boss 13 is provided with a pin 19^a to form a journal for a master key, the function and structure of which will be more fully hereinafter set forth.

It will be understood that the spring 11 95 normally tends to retain the bolt in its locked position so that when the handle 6 is released the bolt is thrown to its left hand position. The bottom of the plate 1 is provided with a lug 20 extending at right angles 100 relative thereto from which extends a threaded orifice 21. Positioned on either side thereof and towards the bottom relative thereto are additional lugs 22 which are utilized to form a support for a coin removal lock that has a part provided to permit the ready removal of coins without interfering with the coin lock assembly.

The cover of the lock structure is illustrated in Figs. 1, 2 and 3 and consists of a 110 cover plate provided with side walls 31 formed integrally therewith so as to com-

pletely enclose the base or back plate 1. In an aligned position relative to shaft 7 I provide a shaft 35 controlled by a handle 36. The shaft 35 has secured thereto on the interior of the case a lever or cam lug 40 which is adapted to move over the face of the bolt 4. This cam lug has formed integrally therewith, or otherwise secured thereto, an angle piece 41 positioned so that when the lock is assembled it is adjacent to the bolt head side of the lock structure. This angle piece is of such shape and size as to cooperate with a curved lug 43 carried at the upper right hand end of the bolt 4, in the view shown in Fig. 4. At the right hand side of the interior of the case of the lock, shown in Fig. 3 (that is, the left hand side of the completed assembly looking from the exterior of the door) I provide two bosses 45 which form a seat for suitable screws 46 in vertical alignment with each other but spaced apart. The screws 46 extend through slots 47 formed in a boss 48 whereby the boss 48 is permitted to move upwardly and downwardly relative to the case by means of the slot therein. The end of the boss 48 is provided with a hook portion 49 curved, as shown, to come into alignment with a keyhole 50 provided in the face of the case. The upper end of the sliding member 48 is provided with an angle piece 51 which is adapted to come in contact with the pin 9 of the bell crank 14 carried by the shaft 7. The lower ends of the sides 31 of the structure are provided with bosses 55 the end surfaces of which form seats for the coin removal lock, and the inner surface of the case is provided with a similar boss 56 to form a bearing for the bolt of the coin lock. The inner surface of the outer case is provided with a boss 20^a provided with an orifice 21^a therethrough which is adapted to come into alignment with the piece 20 of the base plate 1, to permit a screw 60 to be inserted therein to readily hold the parts together at the base. The case is also provided with a smooth faced boss 60' which is positioned in alignment with the smooth surface 61 of the plate, and the top edge of the case is cut away, as shown at 62, flush with the boss 60' to thereby efficiently and economically form a coin chute leading to the coin rests 41 and 43 on the cam 40 and bolt 4, respectively. The top end of the case is also provided with a projecting lug 64 which is adapted to be seated in the lug seat 65 formed in the back of the plate.

In assembling the coin lock of my invention, the plate 1 is screwed into place and the shaft 7 thereof passed through the door and secured to the assembly. The case is then positioned thereon by means of the lug 64 and the lug seat 65, with the parts 20 and 20^a aligned with each other. A suitable screw, for example, a thumb screw, is then utilized to lock the parts 20 and 20^a together, as hereinbefore explained. The removable coin base 70 is then inserted in place at the bottom of the assembly, the same resting against the lugs 55 and 56 and the lock therein projected, for example, by means of the key 71, over the lug 56, it being understood that the lock structure is provided with a groove 72 which fits over the lugs 22 carried by the base plate 1.

From the foregoing it will be seen that when the structure is assembled the handle 36 may be turned at will without effecting the operation of the bolt. As soon, however, as a coin of the proper designation is deposited in the coin slot 61, the coin guide arm 19 deposits the same on the coin rests 41 and 43 formed on the bolt-actuating cam 40 and the bolt 4, respectively, whereby when the handle 36 is next turned the bolt is withdrawn from its locking position through the rotation of the shaft 35, cam 40, coin seat 41, and the coin lug 43, as will readily be apparent, with the result that the bolt is withdrawn from engagement with its latch. The arm 17 of the coin guide assumes the position shown in full lines in Fig. 4 whereby additional coins cannot be inserted into the lock. When the handle 36 is released, the cam 40 and bolt 4 return to normal position, that is with the bolt 5 protruding. As the door is closed the bolt 5 is forced back by reason of its engagement with the plate 80. This carries the coin lug 43 out of engagement with the coin which is then free to drop in the bottom of the case.

It will be apparent in the structure thus described that control of the lock is at all times effective through the operation of the inner handle and is only effective through the operation of the outer handle when a coin of the proper size has been deposited in the lock. If the coin is too small it is apparent that it will pass freely by the coin rests 43 and 41, the size of the slot formed by the members 61, 62 preventing coins of a larger size than that desired from being utilized. When, however, it is desired to operate the door from the exterior without the use of coins, a key, for example, the key 90, is inserted through the orifice 50 in the case on the key pin 19^a. A rotation thereof raises the member 48 so that the angle piece 51 engages the pin 9 of the bell crank lever 14, and thereby through the rotative movement imparted to the bell crank, withdraws the bolt in the manner hereinbefore described.

Many modifications and changes in details will readily occur to those skilled in the art without departing from the spirit and scope of my invention as defined in the claim, and I, therefore, desire to have the foregoing description and illustration of one specific structure embodying the principles of my in-

vention regarded in an illustrative sense rather than in a limiting sense and,

Having now set forth the objects and nature of my invention, and a construction embodying the principles thereof, what I claim as new and useful and of my own invention, and desire to secure by Letters Patent is:—

In a coin lock structure, the combination with a spring bolt, a coin stop on said bolt, a rotatable shaft operatively connected to the bolt to actuate the same in either direction; a second shaft aligned with said first named

shaft for rotative movement independent of said first named shaft, a cam lever on said second shaft, a coin stop on said lever, means for actuating a coin into position between said coin stops to cause the actuation of said bolt actuating shaft through the operation of said independent shaft when a coin is positioned between the coin stops, and independent means for withdrawing said bolt.

In testimony whereof I have hereunto set my hand on this third day of June A. D., 1921.

GEORGE CHAPMAN.
